UNITED STATES PATENT OFFICE

148,806

DESIGN FOR A PHOTOGRAPHIC LAMP HOLDER

Henry T. Lorenz, Chicago, Ill., assignor to Herman Powell, Chicago, Ill.

Application January 8, 1947, Serial No. 135,993

Term of patent 14 years

(Cl. D61—1)

To all whom it may concern:

Be it known that I, Henry T. Lorenz, a citizen of the United States, residing at Chicago, in the county of Cook and State of Illinois, have invented a new, original, and ornamental Design for a Photographic Lamp Holder, of which the following is a specification, reference being had to the accompanying drawing, forming part thereof.

Figure 1 is a front elevational view of a photographic lamp holder showing my new design.

Fig. 2 is a rear elevational view of the side opposite to that shown in Fig. 1.

Figs. 3, 4 and 5 are top, bottom and end views thereof, respectively, the holder being shown fragmentarily in Figs. 3 and 4 for convenience of illustration.

I claim:

The ornamental design for a photographic lamp holder, as shown and described.

HENRY T. LORENZ.
